UNITED STATES PATENT OFFICE

127,723

DESIGN FOR A SHOE

Evelyn Z. Lipari, New York, N. Y.

Application April 19, 1941, Serial No. 100,505

Term of patent 3½ years

To all whom it may concern:

Be it known that I, Evelyn Z. Lipari, a citizen of the United States of America, residing in the city of New York, county of New York, and State of New York, have invented a new, original, and ornamental Design for a Shoe, of which the following is a specification, reference being had to the accompanying drawing, forming part thereof.

Fig. 1 is a plan view of a shoe showing my new design.

Fig. 2 is a front perspective view thereof.

I claim:

The ornamental design for a shoe, as shown.

EVELYN Z. LIPARI.
